WIRELESS SPECIALTY APPARATUS COMPANY, OF BOSTON, MASSACHUSETTS,
A CORPORATION OF NEW YORK.

APPARATUS FOR RADIO COMMUNICATION.

1,127,921.

Specification of Letters Patent.

Patented Feb. 9, 1915.

Continuation of application Serial No. 461,617, filed November 9, 1908. This application filed April 24, 1913.
Serial No. 763,408.

To all whom it may concern:

Be it known that I, GREENLEAF WHITTIER PICKARD, a citizen of the United States of America, and a resident of Amesbury, Massachusetts, have invented certain new and useful Improvements in Apparatus for Radio Communication, the principles of which are set forth in the following specification and accompanying drawing, which disclose the form of the invention which I now consider to be the best of various forms in which the principles of the invention may be embodied.

This application is a continuation of that filed by me November 9, 1908, Serial No. 461,617.

This invention relates to tuning inductances of the type wherein the turns of a winding are mechanically fixed, for use as in the high frequency oscillating-current circuits employed in wireless telegraphy and telephony, or radio communication; and the invention has more particular relation to the receiving arrangements employed in radio communication wherein are employed oscillation-current frequencies of the order of hundreds of thousands per second. Inductance tuners in this art of high frequency currents are, as well known to those skilled therein, of the well-known type in which the coil is wound continuously with turns close together, the successive turns being in mutually inductive relation, and without any core of magnetic material, whereby the coil is adapted as an inductance element of a resonant circuit of the high-frequency oscillating-current art, and whereby such inductance, when variable, is an adjustable tuning element of such resonant oscillatory current circuit. That which I herein specifically term the "mechanically fixed winding type" of high-frequency inductance tuners has inherently certain important advantages over the movable winding type of the same general functioning, but wherein the same object of tuning, (i. e., adjusting the oscillation frequency or natural period of one or more of the resonant high-frequency circuits employed in this branch of the electrical art), is accomplished by unwinding a part of the wire from the tuning coil so that the unwound portion is removed from the field of the coil itself, there-

by decreasing the total inductance of the coil and thence varying the product of inductance and capacity in the high-frequency circuit to the extent desired to obtain the proper tune or natural period thereof. It is not here necessary to specify its points of inferiority to the fixed winding type, on which the present invention is an improvement.

The object of the invention is a simple and efficient device of the "fixed winding type" indicated generally in Figure 1, and to take greater advantage than heretofore of its inherent superiority to the movable winding type, particularly in tuning the high-frequency receiving circuit or circuits of radio communication to electric waves received from a distant radiator or sender.

The fixed winding type has been embodied theoretically in several specific forms, but the one which has been in general use prior to my invention is the movable contact-on-coil type known long prior thereto in the high-frequency current art.

Broadly, the fixed winding type is divided into two classes, one wherein the inductance is cut in or out continuously or gradually, without separate steps, and the other where it is cut in or out by successive steps of greater or less degree. The above contact-on-coil device is an example of the step-by-step method. The continuous method is that where a conductor or contact was shifted along a wire in the resonant high-frequency circuit for the purpose, as its original users stated, of varying the coefficient of self-induction of the wire and thereby adjusting the circuit to a definite period of oscillation-frequency or tune. This continuous-variation method possesses the very important advantage of very fine regulation and close tuning, but is impracticable for commercial operation on account of the excessive range of contact movement required to be made within a very limited time, and on account of the bulky shape of the inductance, both of which are necessarily involved in an apparatus of this type.

The contact-on-coil tuner, of the second type, of step-by-step variation, was used in general practice prior to my invention, in preference to the continuous-variation type,

on account of the above-mentioned practical difficulties involved in the latter, and because the turns of the coil are arranged compactly in successive inductive relation, and because the contacts moved in a straight line along the coil, passing from a position in contact with one turn, only a very short distance into contact with the next closely adjacent turn, and being, therefore, more quickly adjustable than the continuous-variation type. Both the continuous-variation type and the step-by-step type, as used in the practice of radio telegraphy prior to this invention, have been always in a form wherein the contact maker or switch operates directly on the inductance wire, this being for a reason hereinafter explained in connection with certain capacity phenomena. It has been proposed frequently to provide the coil with taps to suitable switch-contacts, but although this expedient has been adopted in other branches of the electrical art, its use in high-frequency current work was prevented by certain difficulties to be described herein which are overcome by the present invention.

Under the more practical step-by-step variation sub-type of the fixed winding type, two distinct methods of control have been suggested, *i. e.*, one wherein the out-of-service portions of the coil are short-circuited, and another wherein the out-of-service portions are simply dead-ended; but as the difference between these two is immaterial to the present invention, it is sufficient simply to refer to the fact.

The specific form of the step-by-step type in most general prior use, has been that of the contact-on-coil, *supra*. Inasmuch as that is the type on which the present invention is an improvement, the invention may be best understood by a brief consideration of the advantages and disadvantages of the former, in connection with the drawings herein. A consideration of the advantages of the contact-on-coil form will show why it continued in commercial use for so many years and until displaced by the present invention and therefore why certain methods employed in it are retained in the present invention; and consideration of the disadvantages of the contact-on-coil system, in connection with the invention disclosed herein will be useful in arriving at an understanding of the care required to be exercised by the constructor in embodying the present invention in practical apparatus, and of the difficulties involved in the problem of overcoming such disadvantages of the prior devices.

Of the drawings, Fig. 1 is an elevation of an inductance tuning apparatus; Fig. 2 is a diagrammatic view showing conventionally the high-frequency resonant circuit A, G to be tuned, such as the antenna or aerial

(A) and ground (G) circuit of a wireless or radio station, and also showing the winding P of Fig. 1 assembled with the switches and other features of the invention, the detailed arrangement of which is shown in Figs. 3 and 4; Fig. 3 is an elevation of the inside of a side of a box adapted to contain the windings of Figs. 1 and 2, this Fig. 3 illustrating the box-wiring and switch contacts; Fig. 4 is an elevation of the box showing the outside thereof, presenting the reverse or outside front of the box-side of Fig. 3; and Figs. 5 to 8 are like diagrammatic illustrations of various electrical forms in which the tuning inductance and switching arrangements may be employed within the invention, in connection with the features more particularly shown in Fig. 3.

Fig. 1 herein indicates generally the self-inductance winding P of the high-frequency coil type (*i. e.*, with non-magnetic core) which may be employed in combination with the arrangements shown in Fig. 3. In Fig. 1 the coil P is shown as wound on a supporting core C, which as a non-magnetic core, may consist of a cylindrical shell of hard rubber. When desired, the coil P may be used with a second coil X on a similar core C, in which case coil P may be the primary and X the secondary of a high-frequency oscillation-transformer. In either case the coil P may be included in the usual antenna-to-ground circuit A, G of radio systems as shown in Fig. 2; and in cases where the secondary X is also employed, as assumed in Fig. 2, in inductive relation to coil P, as in Fig. 1, it will have connected in its circuit the usual, well-known apparatus as used in the radio communication art. In all cases the coil P consists, as shown, of a large number of turns, wound closely adjacent on the core in order to obtain the maximum inductance for a given number of turns, *i. e.*, the greatest wave-length range for the most compact coil. Also in any case if desired, the winding X of Fig. 1 may be combined with the apparatus shown in Figs. 3 and 4 in the same manner as is winding P as described herein, and the user is to have the option of so employing either or both of coils P and X.

The invention embodied herein is more particularly adapted as the receiver employed in radio communication.

The contact-on-coil method, following the earlier practice of the art in tuning by inductance variation, consists in shifting two contacts in a straight line along the outside of a helical coil of wire wound with its successive turns closely adjacent and in mutual inductive relation on a non-magnetic core of the high-frequency coil type, *i. e.*, as if the contacts operated on the winding of the coil P of Fig. 1, along a straight line,

as along the top of the coil, Fig. 1. The two movable contacts were also connected to the two sides of the high-frequency resonant circuit to be tuned, and the movements of the contacts to or from each other caused the inclusion of variable amounts of inductance in the high-frequency circuit, and the cut-off-service parts of the coil, on either side of the contact, being dead-ended.

One reason for the long-continued commercial success of the contact-on-coil apparatus is the fact that it permitted the disposition in compact form of the great lengths of wire arranged in many turns, which are necessary to be used in tuning to widely differing-wave-frequencies within the limits of the extremely high frequencies of the order of hundreds of thousands per second which are employed in the radio telegraph service, this wire being thereby employed in such form that all its parts were successively in mutually inductive relation, and the entire structure, including coil and movable contacts, being of compact and convenient form; all of which said advantages are retained in the coils of the drawings herein, as shown more particularly in Figs. 1, 3 and 4. Another practical advantage of the contact-on-coil device was that it permitted comparatively small variations of inductance, *i. e.*, as small as a single turn of the coil, (as distinguished from methods consisting in the switching in and out of entire groups of coil turns or else substituting alternately coils of differing lengths of wire), this turn-by-turn adjustment being practicable and approximating sufficiently closely for all practical purposes to the close tuning obtained with the continuous-variation type. This advantage is also retained in the present invention, as will be explained in connection with drawings. However, the contact-on-coil method lacked an advantage which existed in the method of switching in definite groups of coil-turns, because in the former it was not possible to determine by inspection what the oscillation period of the circuit might be for any given adjustment of movable contact on the coil and because a sufficiently speedy adjustment could not be made as between two widely differing frequencies within the limits of the high frequencies employed.

Among the other objects of this invention is that of producing a practicable inductance tuner which shall possess the advantages of the gradual variation of that of the contact-on-coil types, and also the advantage of substantially instant determination of the amount of the inductance in circuit for any and all adjustments, as well as the ability to quickly effect large variations of inductance. Such knowledge and ability to operate quickly is of the greatest importance in practical working, that is, when coupled

with the knowledge, acquired by experience, of just the number of turns which puts the circuit in tune with waves arriving from a given distant and known radiator or sending station. In tuning in anticipation of receiving a call from such distant station, or in tuning to waves from such station after a call from it has been received on a broad, general or so-called "stand by" tune, it is of the utmost importance that the receiving operator lose no time in establishing the very best conditions of reception. But even if he knows the wave-length of the distant sender, he must wait until he can determine such best conditions by trial, unless he can instantly shift his tuner into a condition known to correspond with that of the sender. The ability to permit such instantaneous shifting is an important object of this invention.

A further object of this invention is to provide an inductance tuner which shall permit quicker action than that of the contact-on-coil type, in respect of a change of tune involving a variation of a very large number of coil-turns, which in said prior art involves the sliding of a movable contact over possibly many hundreds of turns of wire. It cannot be sufficiently emphasized that it is of the utmost importance in radio practice to enable the receiving operator to adjust his apparatus in the speediest possible manner.

A simple combination of the contact-on-coil method with the group-switching method would consist of an arrangement of the movable contacts of the first-named method along a part of the coil, for small adjustments, and in addition, for the large adjustments, the provision of switches of the second-named method on the coil itself. But another object of this invention is to combine the advantages of both said two methods in a structure which may possess the advantages of both and the disadvantages of neither. A beginning is made by taking the high-frequency coil of the contact-on-coil type, the same consisting of a large number of turns of wire wound on a non-magnetic core, the turns being arranged compactly in a single coil and lying closely together, not only to obtain a compact form, but to secure the best electrical arrangement consisting of the greatest inductance for a given number of turns, *i. e.*, the greatest range in wave-length adjustment for a given number of turns, that is, for a given length of coil or degree of compactness of coil-structure, all as employed in the apparatus shown in the drawings hereof. Next, in combining the small variations of the one method with the large variations of the other method, the plan is generally, in accordance with this invention, to follow the contact-on-coil method consisting in operat-

ing in both directions from the center of the coil. In this method, the amount of inductance included in the high frequency circuit to be tuned at any one time, consists of some inductance on one side of the center of the coil, and also of some more inductance on the other side of the center of the coil. But in the case of this invention, the center of working is not the physical or electrical center of the coil, but an intermediate point nearer one end of the coil than the other, this point being invariable and permanently fixed, and definitely located as distinguished from the contact-on-coil type, all as will be seen.

In accomplishing the above object, an important minor object is to obviate the contact-making disadvantages of the device. These arose from the fact that the many turns were wound so closely together for best electrical effects, and to occupy the smallest space, that in service adjacent turns or groups of turns became short-circuited, by the deposition, between the turns and on the core, of conducting particles resulting from corrosion of the turns and from abrasion of the turns and contacts resulting from the action of contact-shifting. Also the coil-turns became loosened by shrinkage of the core, so that even when they were gold-plated, as was frequently done for the important purpose of preventing the above action of short-circuiting, the contact-making method was at best unsatisfactory and unreliable.

It was not difficult to observe that a way of avoiding the contact difficulties arising from the use of the contact-on-coil device, was to employ taps from the coil-turns leading to suitable switches. In fact that was a common expedient of the general electrical art including such devices as rheostats and ordinary low-frequency alternating-current potential regulators using currents of a frequency of the order of a hundred per second, more or less, as contrasted with the frequencies of hundreds of thousands per second which are employed in the high-frequency-current art to which this invention relates. But such an expedient seemed utterly impracticable in this instance, where the high-frequency or oscillating currents employed result in certain capacity effects between two neighboring conductors which are liable to affect the integrity of the high frequency resonant circuit. Where it was of the essence of the inductance tuner that the hundreds of coil-turns should be close together and that the tuning regulation should be very close, *i. e.* preferably not less than approximately one coil-turn per step, it was seemingly impossible to devise an arrangement of taps from the successive coil-turns which would not involve substantial capacity effects between such taps which

would affect the circuit of the coil deleteriously. In this capacity difficulty lies the most probable explanation of the unquestionable fact of the art's long-continued use of the inferior contact-on-coil type.

The capacity action in question is as follows: The electrostatic capacity between the conductors carrying high frequency currents, such as taps from such an inductance tuning coil, acts as a shunt path from one tap to another across the dielectric space between them, and this effective shunt path diverts part of the current from its normal path through the resonant circuit containing the coil itself, the result being that the portion of the coil included between such taps as have electrostatic capacity between them, is short-circuited to a greater or less degree depending upon the degree of the capacity existing between such taps. Now such degree of capacity short-circuiting across the taps from the coil tends to form in effect a closed circuit, or a series of closed circuits corresponding to successive pairs of taps, containing capacity and inductance (*i. e.*, the capacity between the taps and the inductance of the portion of the coil itself included between them), such circuits being thereby resonant with some particular frequency or set of frequencies, depending on the product of the capacity and inductance in any given case. Such parasitic circuits interfere with the proper tuning of the resonant circuit to be tuned by the inductance variation, this interference being due to the harmful absorption by such parasitic circuits of parts of the energy of the circuit to be tuned, when the latter is so adjusted as to operate at the same frequency as any of said other resonant circuits. That is, under such conditions, the tuning inductance would be liable to have spots of bad working corresponding to the fortuitous frequencies of such parasitic circuits. Notwithstanding these difficulties, it seemed inevitable that the main object of the invention, (*i. e.*, a consolidation of the advantages of the various prior methods into one practicable device in such manner as to obviate their disadvantages), must involve some method of employing taps from the coil-turns to suitable switches. For this reason the problem of the parasitic currents, the practical solution of which thus became the ultimate essential object of the invention, was attacked and solved in the manner disclosed herein.

The specific object to be accomplished, in order that the broader objects of the invention, above stated, might be accomplished, was through the reduction of the parasitic currents to a negligible minimum. This may be effected to a degree, by making the taps as short as possible, and particularly by keeping them as far apart as possible. Short taps are consistent with the essential of a

coil with closely adjacent turns, but short taps and such a coil seemed inconsistent with sufficient spaces between the taps to prevent harmful capacity effects, particularly if the 5 entire apparatus were to be kept within reasonable space limits and without too long taps; and, for electrical reasons, as well as from a desire for compactness, it was not permissible in the case of these high frequency circuits (as it would be in the general electrical art of low frequency alternating currents) to wind the turns of the coil sufficiently far apart so that the taps from such separated turns would involve no harmful 10 parasitic currents. Thus the problem was reduced down to some other method of eliminating the parasitic currents. This specific object of the invention is accomplished in the apparatus disclosed herein, by 15 expedients so employed as to substantially eliminate all possible danger of parasitic currents. One of the more important of these expedients consists in allowing for sufficient space between the taps by reducing 20 the number of the taps in such way as not to reduce the small regulations of the tuner. Among various other minor expedients is that which consists in providing means for so fixing the taps in position that they can- 25 not assume such relative positions as shall produce harmful parasitic currents.

The invention is best shown in Figs. 3 and 4, since Figs. 1 and 2 are largely dia- 30 grammatic and Fig. 1 lacks a showing of all the important details of the invention.

The invention will be best understood with particular reference to Fig. 3, which shows the essential features of the connections from the coil-turns to the box-wiring, from 35 the latter to the switch-contacts, and from the latter to the switches and thence to the high frequency circuit, such as A, G, of Fig. 2, in which the coil is connected. In Fig. 3 is shown the inside or back of a board of 40 side D of a box containing the coil or coils of Fig. 1, the front or outside of this board or box-front being shown in Fig. 4. This board of Fig. 3 contains all the essential features of the invention auxiliary to the 45 coil itself, the rest of the box being omitted, because it is used merely for the purpose of inclosing, supporting and protecting the coils. In effect and actually, the side-board D of Fig. 3 is a panel on which is mounted 50 all the apparatus, including the switches and connections to which the coil or coils of Fig. 1 are connected. On the front of the board or panel D in Fig. 4 are only the operative surfaces of the contacts of the switches and 55 also the movable switch arms S, S¹.

The apparatus mounted on the back or inside of the panel board, shown in Fig. 3, is as follows, the same constituting a permanent part of the panel and being com- 60 bined therewith prior to the mounting in

place in the box, of the coils of Fig. 1. Two groups of connections are provided, one to and from connectors 0^b-2^b, 3^c-7^c, and 8^b-10^b, and another to connectors 0^d, and 10^b-9^b. The numerals correspond with the numerals on the taps from the coil, as noted in Figs. 1 and 2. The "b" connectors are intermediate between the coil-taps and the "c" connectors. The "b" connectors are connected with the "c" connectors by box-wiring or 70 coil-tap-continuations M and N. The "b" connectors may be employed when it is found necessary or desirable by such means to support the taps which extend intermediate the coil and the "c" connectors, for the purpose of keeping such taps separate from each other. This feature may be employed usefully also for the purpose of facilitating assemblage, particularly in such a case as in Fig. 3 when the connectors 10^c-9^c are remote from the open bottom of the box and hence not readily accessible for the purpose of connecting taps from the coil directly to said connectors 10^c-9^c, the coil itself being in place close to the panel D in order to permit the shortest possible coil-taps, and in such position making the connectors 10^c-9^c yet more difficult of access. An important remaining feature of the arrangement on panel D is the connection between connectors 0^b and 0^d by way of lead M, connector 0^c and 1^c. By means of this system of panel 75 connections, both connectors 0^c and 0^d are connected to the same fixed point of the coil, so that the two sets of connectors 0^c-10^c and 10^b-9^b are made coöperative. The coil tap 0 of Fig. 1 is connected to the connector 0^b (Fig. 3), and it is from this fixed intermediate point of the coil that tuning operations are conducted in opposite directions 80 along the coil, and in such way that the operations are continuous in the sense desirable for best tuning, *i. e.*, that all portions of the coil in circuit at any one time are continuous between their extreme opposite ends, including the point 0 and all the wire adjacent to that point on each side of it, this being the arrangement most highly preferred and the one made possible to perfection by the general arrangement hereof. 85 Thus the advantage of the prior art is retained, consisting in operating in both directions from the middle of the coil, as above explained, and in this respect following the practice employed with the contact-on-coil type, save that here the intermediate point is one which is definitely and permanently fixed. But in the case of the present improvement on that type, wherein taps are 90 taken from the coil to switch-contacts, there would be hundreds of taps if one were taken from each turn of the coil for small adjustments throughout the length of the coil, and this I believe would cause serious parasitic currents in any practicable coil. In order to 95

obviate this difficulty I omit all taps on one side of the intermediate or common fixed point 0 save one for each group of a desired number of turns. In order to provide for small adjustments, (as well as for the larger adjustments permitted by the above reduction of coil-taps) while retaining the method of adjusting on both sides of the intermediate or fixed common point 0 of the coil, I employ the connection of that point to the two contacts 0^a , 0^d (Fig. 3) of the two separate switches S , S^1 (by the connections of Fig. 3 above described), and in addition I lead taps from small subdivisions of the part of the coil (right, Fig. 1) which lies on the other side of the intermediate point 0, so that one switch operates to cut in or out small parts of the coil on that (right) side of said zero point, while the other switch operates to cut in or out larger parts of the coil on the other (left) side of the zero point of the coil; the two switches coöperating to cut in or out varying total amounts of inductance of the coil, which amounts are always continuously and successively adjacent, and inclusive of the common zero point, between the extreme limits of the total portions of the coil which are cut into the high frequency circuit at any one time. Thus in addition to the obviation of difficulties of tap-capacity and parasitic currents, by reducing the number of taps by omitting all those made unnecessary to use by the employment of the above expedient, I obtain also the further advantage of obtaining large and small adjustments without the necessity of employing a separate switch contact for every one of the hundreds of turns of the coil, inasmuch as the few needed taps for the small or unit adjustments may include between them as small portions of the coil as may be desired for the fine regulation, when coöperating, as above, with the larger units consisting of several coil-turns, so that any desired number of small units may be included in the high frequency circuit at any one time.

I have been informed since the completion of the improvements herein, that an expedient similar to that herein employed to reduce the parasitic current difficulty with the accompanying convenience in adjustment over the wide ranges of inductance employed in radio receiving apparatus, has been employed in the general electrical art in connection with so-called dial-rheostats and in regulators of potentials in low-frequency alternating current transformers, etc. I believe, however, that I was the first to employ the above-described expedient consisting in reducing the number of coil-taps in connection with high frequency apparatus (and particularly a single coil with many turns wound closely adjacent on a common non-magnetic core) and with the object of reducing the parasitic current difficulty which is essentially involved in the action of such apparatus as distinguished from the apparatus of the other arts above referred to. I believe also that I was the first to conceive and execute the idea of employing said expedient as a means to permit a practicable departure from the contact-on-coil type of inductance-tuning devices previously employed for many years in the art of radio communication.

In Fig. 2 the system of connections here shown diagrammatically in simpler and slightly modified form as compared with Fig. 3. Here the contacts 0^a - 40^a of the lower or large-adjustment switch S correspond with the lower set of "b" and "c" connectors of Fig. 3; and the contacts 0^a - 10^a of the upper or small-adjustment switch S^1 correspond with the upper set of "b" and "c" connectors of Fig. 3, the leads from these contacts of Fig. 2 being connected to the taps 0 - 10 and 0 - 40 *et seq.*, extending from the coil as shown in both Figs. 2 and 1. The connecting common lead L (Fig. 3) between switch-connectors 0^a and 0^d is lacking in the simplified diagram of Fig. 2 however; the equivalent arrangement there being a single lead L to a contact 0^a which is common to both switches S and S^1 . Other methods of obtaining the effective common zero arrangement are shown in Figs. 5-8, but I prefer the arrangement of Fig. 3, wherein each switch is provided with a separate complete set of contacts, all as more clearly shown in Fig. 4 which illustrates the opposite side of panel D from that shown in Fig. 3. Here are shown the operative switch contacts with switches S and S^1 in operative position. The two switches here operate reversely, their common zero being at their contacts 0^a and 0^d respectively, the maximum position of switch S^1 being at the right at contact 10^a , and the maximum position of switch S being at the left at contact 90^a . In the switch-positions shown, there are thirty-nine turns of the coil in circuit, as is readily determined by inspection of the switch-positions and the contact numerals, assuming that the numerals indicate the number of coil turns cut in circuit by a given switch at a given contact, this being the preferred method. Any desired marking may be used on the contacts, such as a wave-length reading, but that is not preferred because it would not be standard for the different capacities of different antennæ A, G. If desired, the switches may operate in the same direction, instead of opposite directions as in Fig. 3, this being accomplished by crossing the taps leading from one part of the coil to the contacts of one of the switches, and thereby reversing the order of succession of the contacts for that switch. Other

suitable methods of obtaining the same effect are disclosed hereinafter. Various other arrangements equivalent to that of Figs. 3 and 4 are shown in Figs. 5-8 described hereinafter, but the operation of all is substantially the same and may be described generally in terms of that of Figs. 3 and 4, the switch-contacts being marked to correspond with the number of coil turns in circuit, as shown. The tuning operations may be conducted by the operator with the assurance that the effect in tuning the high frequency circuit is uniform throughout the entire length of the inductance, *i. e.*, that there are no spots of inaccurate working on the coil resulting from parasitic currents due to the capacity of the taps and leads from the coils to the switch contacts, and with the assurance that there are no inaccuracies due to the omission from the resonant circuit of any portion of the coil intervening between the extreme ends of the total portions of the coil in circuit at any given time. In fact, when the number of taps is reduced by the expedients above described, there is so little deleterious action of parasitic currents that it becomes of much less importance than was anticipated to physically separate the taps from each other, in an apparatus of a given size, and the results of the operation of this invention seem to show that the naturally expected difficulties of parasitic currents in connection with these circuits of extremely high oscillation-frequency was considerably exaggerated as an obstacle in the minds of the prior workers in the radio art.

In operation, let it be assumed that the switches of Fig. 3 are set at some general or "stand-by" tune, such as the radio receiving operator has found to be suitable for receiving messages from different senders, composed of widely different wave-lengths, say from three hundred meters to six hundred meters, up to five thousand meters, corresponding to frequencies per second of one million, one-half million, and one hundred and eighty-seven thousand respectively. This "stand-by" tune might, for example, be that to which the switches of Fig. 4 are shown as adjusted, *i. e.*, one corresponding to a tuner inductance for thirty-nine turns; which might be a suitable inductance adjustment, depending on the antenna, etc., for a six hundred meter wave having a frequency of a half-million per second. (It is understood that the coil P of Fig. 1 may comprise many hundreds of turns, in order to be adapted to tune accurately and closely to any particular wave-length and frequency within the very wide limits employed in practice.) The operator then receives a "call" intended for him and "signed" by a distant sending station known to him from experience as having its

waves best received by him on a given adjustment of the switches S and S¹, say for example, one corresponding to a tuner inductance of seventy-three turns, and say of a thousand meter wave-length with a frequency of three hundred thousand per second. All that the operator has to do, (and this without any danger of faulty adjustment due to parasitic currents from hundreds of tap-leads in the box from the coil to the switch contacts), is to adjust the lower switch (Fig. 4) to contact 70 and the upper switch to contact 3. On the other hand, if the distant sender has a wavelength unknown to the operator, he need not experiment by making contacts throughout each of the hundreds of turns throughout the length of the coil, but only with the large-adjustment (lower) switch S over a few contacts, and then, for perfect tune, with the small adjustment (upper) switch S¹ over a few contacts, this entire tuning by trial occupying only a few seconds before he is ready to signal for the distant sender to proceed with its message. The receiving operator may make a record of this adjustment for this particular sender, so that the next time it calls he can instantly set his tuner at the proper adjustment without any trial whatsoever. The receiving operator is in all cases assured, by the lack of danger from parasitic currents, that the tune which gives the best results to him is in fact the best adjustment, *i. e.*, the exact tune of the waves being received, and not some other and inefficient tune which might give the best results to him because of parasitic and energy-consuming currents resulting from tap-capacity action, but not the best results possible with a perfectly efficient tuner such as this. Furthermore, this successful solution of the parasitic current problems carries with it an elimination of all the contact difficulties above described as accompanying contact-shifting action directly on the wire turns of the coil itself.

As is indicated in Figs. 1 and 2, the variation of the inductance of coil P in the circuit of the grounded antenna A, G, serves not only to tune the antenna to the period of the waves being received, but also to vary the coupling of the primary and secondary circuits. The coils P, X, constitute an oscillation-transformer, which, owing to the lack of a magnetic core, provides a loose coupling between the primary circuit or receiving antenna and the circuit of secondary X which contains the usual receiving apparatus, and this loose coupling in turn provides mutual independence of the two circuits in respect of selectivity, and permits a transfer of energy by resonance from the antenna to the secondary circuit. Thus the action of this tuner in varying the coupling and consequent selectivity of the sys-

tem, as well as in varying the antenna-period, is very advantageous in respect of its uniformity of action resulting from the described improvements.

In Fig. 5 is shown an arrangement like that of Figs. 1 and 3, except that two leads L^2 , L^3 are taken from neighboring parts of the coil to respective zero contacts of the two switches, said zero contacts being connected by lead L^4 , thus providing a common zero connection for the two switches, whereby any desired number of turn units may be connected in circuit. In this case, as in Fig. 1, all the turns are in the same direction, *i. e.*, clockwise, or as a right handed thread. The operation of the two switches is most efficient, (it being in effect the same as in Fig. 2), because the current flow is in the same direction through all the turns included in circuit by the switches, owing to the same direction of winding throughout. The arrangement of switch contacts is as in Fig. 4, *i. e.*, from left to right for units, and from right to left for tens, but, as described in connection with Fig. 4, arrangements may be made so that both switches may operate in the same direction.

In Fig. 6 the left hand portion of the coil is clockwise and the right hand portion is anti-clockwise, so that if the common zero connection of the two switches were tapped from the same point (*i. e.*, the point of contiguity of the two parts of the coil as in Fig. 1), the current would be in opposite directions, in accordance with the opposite direction of winding. However, to correct this, the common zero connection is made as follows: The zero taps L^5 , L^6 are taken from the two right hand ends of the coil-parts, and these taps are connected by lead L^7 , whereby the current is in a uniform direction throughout, as indicated by the arrows. Also the unit switch contacts will be from right to left, in ascending order, as shown, the same direction of reading as that of the tens, and this without crossing the taps as described in connection with Fig. 4. Thus this arrangement of Fig. 6 is substantially as efficient as that of Figs. 2 and 5, the slight inferiority in Fig. 6 consisting in the fact that for an operation which includes less than the total number of unit turns, there will be idle turns between the right hand end of the tens coil-part and the unit switch contact then in service. But in Fig. 6, as in the previous figures, the effect of cutting in additional unit turns by switch S^1 is to add to the effective inductance in circuit.

In Fig. 7 all the turns are wound in the same (*i. e.*, clockwise) direction, as in Fig. 5. The zero taps, L^8 , L^9 , L^{10} are led off as in Fig. 6 however, and the direction of succession of the switch contacts is the same

as in Fig. 6, the current direction being therefore opposite in the two coil portions, as indicated by the arrows, and consequently the effect of cutting in unit turns by S^1 is to proportionately reduce the effective inductance, the common zero connection being effective, as in the other cases, in permitting both switches to coöperate in including any desired number of turn-units in the circuit.

In Fig. 8 the portion of the winding on the left is clockwise, while that on the right hand portion is anti-clockwise, whereby the current in the two is in opposite directions. But the specific common zero connection is similar to that of Fig. 5, as shown at L^{11} , L^{12} so that the effect of cutting in unit turns is to reduce the effective inductance in circuit, as in the same of Fig. 7; the common zero connection, as in Fig. 7 as well as in all the other figures, being to coöperate to include any desired number of turn-units in the circuit to be tuned.

I claim:—

1. In an apparatus for radio communication, means for tuning to resonance by inductance variation, a high-frequency oscillation-circuit of a receiving station, which comprises a high-frequency inductance coil consisting of many turns of wire arranged around a non-magnetic core and closely adjacent to each other successively to provide maximum self-induction and wave-length-range for minimum distance between the ends of the coil; in combination with a switch-panel arranged alongside said coil; switch-connectors mounted on the same side of said panel as said inductance coil; two switches with their contacts, mounted on the other side of said panel, the arms of the switches being adapted for connection with the high-frequency circuit to be brought to resonance, and the switch-contacts being connected with said switch-connectors on the coil-side of the panel; intervening connectors mounted on the coil-side of said panel; leads connecting the switch-connectors with said intervening connectors, and leads or taps from said intervening connectors to said inductance coil; the connections and taps from the switch-contacts of each switch to the coil being of limited number and thereby avoiding serious parasitic currents, by means of an arrangement consisting in making the connections from the switch-contacts of one switch, only to points of the coil which are separated by relatively large portions of the coil, over a portion of the coil up to a definite intermediate point, and in providing for smaller adjustments by making the connections from the switch-contacts of the other switch to points of the coil beyond said intermediate point which are separated by relatively small portions of the coil; and

means for connecting said fixed point of the coil intermediate the large and small subdivisions thereof, with both said switch sets, whereby they both coöperate to cut 5 into the high-frequency circuit to be tuned, large and small units of inductance on opposite sides of said fixed intermediate point of zero inductance in circuit.

2. In an apparatus for radio communication, means for tuning to resonance by inductance variation, a high-frequency oscillation-circuit of a receiving station, which comprises a high-frequency inductance-coil consisting of many turns of wire arranged around a non-magnetic core and closely adjacent to each other successively to provide maximum self-induction and wave-length-range for minimum distance between the ends of the coil; in combination 10 with a switch-panel arranged alongside said coil; switch-connectors mounted on the same side of said panel as said inductance coil; two switches with their contacts, mounted on the other side of said panel, the 15 arms of the switches being adapted for connection with the high-frequency circuit to be brought to resonance, and the switch-contacts being connected with said switch-connectors on the coil-side of the panel;

and connections from said switch-connectors to the high-frequency inductance coil, said connections being limited in number and thereby avoiding serious parasitic currents, by means of an arrangement consisting in making the connections from the 20 switch-contacts of one switch, only to points of the coil which are separated by relatively large portions of the coil, over a portion of the coil up to a definite intermediate point, and in providing for 25 smaller adjustments by making the connections from the switch-contacts of the other switch to points of the coil beyond said intermediate point, which are separated by relatively small portions of the 30 coil; and means for connecting said fixed point of the coil intermediate the large and small subdivisions thereof, with both said switch sets whereby they both coöperate to 35 cut into the high-frequency circuit to be 40 tuned, large and small units of inductance 45 on opposite sides of said fixed intermediate point of zero inductance in circuit.
